UNITED STATES PATENT OFFICE

ERVIE A. FERRIS, OF WESTWOOD, CALIFORNIA

RETARD DEVICE

Application filed May 9, 1930. Serial No. 451,158.

My invention relates to improvements in retard devices, and it consists in the combinations, constructions and arrangements hereinafter described and claimed.

- 5 An object of my invention is to provide a retard device which is an improvement over a similar device shown in my co-pending application Serial No. 286,399 filed June 18, 1928, on tong dogs for saw mill carriages.
- 10 In said application a retard device formed an integral part with a casting having a plurality of valves. The present device may be used on any fluid pressure cylinder where it is necessary to have high and slow speed
- 15 strokes of the piston.

In the present invention the retard device is a separate unit, and it employs novel means for regulating the flow of air or other fluid from a small amount to a large amount. In addition to this, adjustable means is provided for restricting the size of the fluid passageway. The device has one moving part, and this part moves in one direction by gravity with the aid of the pressure of the fluid in trying to go through the partially restricted passageway.

A further object of my invention is to provide a device of the type described which is extremely simple in construction and which is durable and efficient for the purpose intended.

Other objects and advantages will appear as the specification proceeds, and the novel features of the device will be particularly pointed out in the claims hereto annexed.

My invention is illustrated in the accompanying drawing, in which:

Figure 1 is a vertical section through the device, portions being shown in elevation,

40 Figure 2 is a side elevation, and

Figure 3 is a top plan view.

In carrying out my invention I provide a casting 1 having a fluid passageway 2 therein and a cylinder 3 for receiving a piston indicated generally at 4. The bottom of the casting is threaded as at 5 and receives a cap 6 which in turn carries a fluid-conveying pipe 7.

50 A fluid-conveying pipe 8 is threaded into one end of the passageway 2, and a second

fluid-conveying pipe 9 is threaded into the opposite end of the passageway 2. The purpose of the piston 4 is to restrict the passageway 2 for slowing up the flow of fluid from the pipe 8 into the pipe 9.

55 It will be noted that the piston 4 has a plunger 10 that is slidably received in a bore 11 which in turn connects the passageway 2 with the cylinder 3. A shoulder 12 is provided on the plunger 10 and limits the movement of the plunger into the passageway 2. I have shown the plunger as being fully extended into the passageway 2 in Figure 1.

60 Cup-shaped members 13 and 14 forming a part of the piston 4 are separated from each other by a disc 15, and all three members are connected to the plunger 10 by a screw 16. The head of the screw bears against a block 17 which in turn is seated in the cup 14. Parts 10, 13, 14, 15, 16 and 17 move as a unit.

65 I also provide manually adjustable means for restricting the passageway 2. A screw 18 is threaded into the casting 1 and has its inner end adapted to enter the passageway 2. A lock nut 19 is provided on the screw, and this nut may be moved into locking position after the screw has been adjusted. In Figure 1 I show the screw as partially entering the passageway 2.

70 From the foregoing description of the various parts of the device, the operation thereof may be readily understood.

75 The fluid to be controlled flows through the pipes 8 and 9 and the passageway 2. The flow may be in either direction. Fluid is also designed to enter the pipe 7 at the will of the operator or by automatic means (not shown) for lifting the piston 4 into the full line position shown in Figure 1. This causes the plunger 10 to enter the passageway 2 and to restrict the flow of fluid through the passageway. The fluid will thus be restricted so long as the piston 4 is maintained in raised position. The freeing of the pressure on the fluid in the pipe 7 will permit the piston 4 to drop by gravity. The pressure of the fluid in the passageway 2 will be equal in all directions, and therefore this fluid will press against the top of the plunger 10 and will aid in moving the plunger into its lowermost po-

sition. When the plunger is in this position, the passageway 2 is unrestricted except for that portion of the screw 18 that extends into the passageway.

5 The screw 18 is designed for permanently restricting the passageway to the desired extent. It is obvious that if the operator wishes, the screw 18 may be moved in to the passageway 2 until it abuts the plunger 10 when 10 the latter is in raised position. This would cut off the flow of fluid through the passageway 2. The drawing illustrates a mere restricting of the passageway 2 when the plunger 10 is fully raised.

15 The device is extremely simple in construction and is designed to be automatically actuated when used in connection with the device set forth in the application referred to in the first part of the specification.

20 Although I have shown and described one embodiment of my invention, it is to be understood that the same is susceptible of various changes, and I reserve the right to employ such changes as may come within the 25 scope of the claims hereto annexed.

I claim:

30 A fluid control device comprising a body having a passage for fluid, a plunger extending at right angles to the passage and designed to be moved into the passage for cutting down the flow of fluid therethrough, a piston connected to the plunger and actuated by fluid for moving the plunger, and a 35 manually adjustable passageway-restricting member movable into the passage for cutting down the size of the passage and adapted to serve as a stop for the movement of the plunger in one direction.

35 Signed at Westwood in the county of Los Angeles and State of California this 1st day of May, A. D. 1930.
